UNITED STATES PATENT OFFICE.

EARL R. HAMILTON, OF PEKIN, INDIANA.

TUBE HOLDING AND COMPRESSING MEANS.

Original application filed April 2, 1925, Serial No. 20,213. Divided and this application filed August 6, 1925. Serial No. 48,587.

To all whom it may concern:

Be it known that I, EARL R. HAMILTON, a citizen of the United States, residing at Pekin, in the county of Washington and 5 State of Indiana, have invented certain new and useful Improvements in Tube Holding and Compressing Means; and I do declare the following to be a full, clear, and exact description of the invention, such as will 10 enable others skilled in the art to which it appertains to make and use the same.

This application relates to improvements in means for holding and compressing collapsible tubes, such as those in which various 15 kinds of pastes are marketed, and the invention is intended primarily for use in connection with an applicator to which the contents of the tube are delivered when said tube is compressed or collapsed. The applicator construction, while illustrated herein in a general way, is claimed in my parent 20 U. S. application Serial Number 20,213, filed April 2, 1925 and the present application forms a division of said parent case.

25 One object of the invention is to provide a new and improved form of holder for a collapsible tube, so constructed that it may readily be carried from place to place or compactly stored without danger of leakage, provision being made whereby an empty 30 tube may readily be removed and a new tube substituted therefor.

Another object is to provide an exceptionally simple and inexpensive, yet an efficient 35 and reliable means for compressing the tube to discharge its contents.

With the foregoing in view, the invention resides in the novel subject matter herein-after described and claimed, the description 40 being supplemented by the accompanying drawing.

Figure 1 is a longitudinal sectional view.

Figure 2 is an enlarged detail sectional 45 view through a portion of the tube compressing means.

Figure 3 is a transverse sectional view on line 3—3 of Figure 1.

In the drawings above briefly described, which may be considered as disclosing the 50 preferred form of construction, the numeral 1 designates an elongated tube which is preferably formed of metal, said tube being provided at its upper end with a permanent stationary closure 2, while a removable closure 3 is provided for its lower end. This removable closure is preferably stamped

from sheet metal, in substantially the form of a cup, and the upper or inner portion of the continuous side wall 4, of said closure, is receivable removably in the lower end of the casing 1, any desired quick detachable connection being provided between the two. Preferably, the wall 4 is formed with headed studs 5 and bayonet slots 6 are provided in the casing wall to engage said studs. Between its upper and lower ends, the wall 4 is provided with an outwardly stamped, externally serrated portion 7 constituting a rib which may readily be gripped when the closure 3 is to be either removed or applied. 70 When in operative position, this rib of the closure 3, abuts the lower end of the tubular casing 1.

In the construction shown, the bottom portion of the closure 3 is formed with an opening and with an annular depending flange 8 around the same. Within this flange, the upper end of a tubular discharge neck 9 is secured in any desired manner, the upper end of said neck being internally threaded 80 as at 10 for engagement with the usual discharge neck 11 of a compressible tube 12 receivable in the casing 1. The lower end of the neck 9 is here shown as provided with an applicator 13 whose construction is fully 85 described and claimed in the parent application above referred to. The part designated at 14, is merely a pin normally closing the neck, which pin is withdrawn when it is desired to discharge some of the contents 90 from the tube 12.

I have provided novel means for compressing the tube 12 to discharge its contents. 27 designates a ram located in the casing 1 and adapted to engage the upper end of the 95 above mentioned tube. This ram may well be in the form of a flat plate and it is carried by the lower end of a bar 28 disposed longitudinally in the casing, the upper end of said bar being preferably, though not necessarily bent into C-shape as indicated at 29, the arms of the C, and ram 27, being formed with aligned openings 30. A nut 31 is non-rotatably held between the above-named arms of the C-shape formation 29, and a longitudinal screw 32 is threaded through this nut, said screw passing slidably through the openings 30. The upper end of the screw is swiveled as at 33 in the closed end 2 of the casing 1, and is provided with an appropriate operating handle 34 by means of which the screw may readily be rotated. Obvious-

ly, by turning this handle in the proper direction, the ram 27 will be forced downwardly, thus compressing the tube 12 for the purpose of discharging its contents to the applicator head, in desired quantities.

To normally cover the applicator head and associated parts, thus effectively protecting them against dust and the like and also preventing soiling of articles by coming in contact with said head, I have provided a cap 35 to enclose these parts. This cap fits frictionally over the lower end portion of the annular side wall 4 of the closure 3 and abuts the lower side of the rib 7. When inserting a new tube into the casing 1 or removing an old one, the closure 3 is entirely detached from said casing 1 and may at that time carry with it the cap 35. Then, the screw threads 10 are readily accessible so that the new tube may readily be inserted after the removal of one whose contents have been discharged.

As excellent results are obtainable from the details disclosed they are preferably followed. However, within the scope of the invention as claimed, modifications may be made.

I claim:

1. A device of the class described comprising a tubular casing, a ram therein, a longitudinal bar in the casing carrying said ram at one of its ends and having its other end bent to form a C-shaped socket, the arms of the socket and said ram having aligned openings, a nut held in said socket, and a screw 35 swiveled in said casing and passing slidably through the aforesaid openings and threaded through said nut.

2. A device of the class described comprising a tubular casing, a ram therein having an opening near one edge, a longitudinal bar in the casing fixed at one end to the ram and having its other end bent laterally, the laterally bent portion having an opening aligned with the opening in the ram, a nut 45 carried and supported by and secured against axial movement independently of and by said laterally bent portion, and a screw swiveled in said casing and passing slidably through the aforesaid openings and 50 threaded through said nut.

In testimony whereof I have hereunto affixed my signature.

EARL R. HAMILTON.
